UNITED STATES PATENT OFFICE

2,041,901

MANUFACTURE OF SOLES

James Cavanagh, Cohasset, Mass., assignor to
 United Shoe Machinery Corporation, Paterson,
 N. J., a corporation of New Jersey

Application December 17, 1934, Serial No. 757,834

6 Claims. (Cl. 36—22)

This invention relates to improvements in the manufacture of soles for boots and shoes.

It is desirable to have the soles of boots and shoes flexible in their foreparts so that they will bend freely as required to accommodate the natural flexure of the feet in walking, i. e., about axes extending crosswise of the sole, and it is also desirable in most shoes to have the soles relatively stiff or relatively inflexible at right angles to the directions in which they are bent in use, i. e., about axes extending lengthwise of the sole. This is particularly true with respect to insoles and more especially with respect to the insoles of shoes of the type in which the margin of the upper is overlasted upon the insoles and is directly secured to both the insole and the outsole by means, for example, of through-and-through stitching or cement.

In view of the foregoing, objects of the present invention are to provide an improved sole having the desired characteristics above pointed out and an improved method of making such soles.

To the accomplishment of the above objects the invention, in one aspect, provides a method of making soles, which are relatively flexible about transverse axes and relatively inflexible about longitudinal axes, which consists in grooving one side of a sole in a crosswise direction, and applying stiffening material to those portions only of the sole which constitute the walls of the grooves. As herein exemplified with respect to the treatment of insoles, a substantial number of grooves are cut in the forepart portion of the lower surface of an insole, that is, the surface which is to face the outsole in the shoe, and the walls of the grooves and the portions of the sole material immediately adjacent to the walls of the grooves are stiffened by the application thereto of a liquid stiffening medium, such for example as pyroxylin cement. A sole thus treated will be reinforced to a substantial extent by means of the stiffening medium against bending about axes extending crosswise of the grooves. On the other hand, the resistance of the sole to bending about axes extending lengthwise of the grooves has been reduced by the grooving operation. Inasmuch as the sole has been made thinner along the lines of the grooves and while the sole substance has been stiffened along the lines of the grooves, the depth of the grooves and the thickness of the coatings of stiffening material are made such that in practice the soles have been found to flex more freely in directions in which they are required to bend in use than soles which have not been thus treated.

Considered in another aspect, invention is to be recognized as residing in an improved sole for shoes having a plurality of grooves extending crosswise of the sole, the walls of the grooves being reinforced by stiffening material, for example, pyroxylin cement.

The invention will be explained with reference to the accompanying drawing, in which

Fig. 1 is a perspective view of the forepart of an insole which has been treated in accordance with the present invention;

Fig. 2 is a fragmentary sectional view illustrating the operation of forming the grooves in the sole;

Fig. 3 is a fragmentary sectional view taken along the line III—III of Fig. 1 as the sole appears before the stiffening medium has been applied;

Figs. 4 and 5 are views similar to Fig. 3 but showing alternative forms of grooves;

Fig. 6 is a fragmentary sectional view illustrating the manner of applying the stiffening medium to the grooved portions of the sole; and

Figs. 7 and 8 are sectional views similar, respectively, to Figs. 3 and 5 but showing the soles as they appear after the stiffening medium has been applied.

In carrying out my improved method I prefer to provide a plurality of grooves 10 in an insole 12 substantially as indicated in Fig. 1, the grooves 30 being preferably formed in the lower or outsole-engaging surface of the forepart portion of the insole and preferably the grooves extend entirely across the insole in directions substantially parallel to the break line, i. e., the line where the 35 sole breaks or bends in the shoe at the junction of its shank and forepart portions. As indicated in Fig. 2, the series of grooves may advantageously be formed in a single operation by means of a machine comprising toothed upper and lower 40 feed wheels 14, 15, a work supporting table 16, through which the lower feed wheel projects, and a series of grooving knives, one of which is shown at 18, to which the insole is advanced by means of the feed rolls. The grooving knives 45 18 may be shaped to form grooves which are arcuate in cross-section, as indicated in Figs. 1, 3 and 7, or they may be shaped to form substantially rectangular grooves, such as the grooves 100 shown in Fig. 4, or V-shaped grooves, such 50 as the grooves 102 shown in Figs. 5 and 8.

After a sole has been grooved in the manner already described the grooved portions of the sole are stiffened, as herein shown, by coating 55 the walls of the grooves with a liquid stiffening

medium, such as pyroxylin cement, the coatings of cement being indicated at 20 in Figs. 6 and 7, and at 200 in Fig. 8. The liquid stiffening medium may be applied to the grooves in a sole 5 by means of a series of extruding nozzles, one of which is shown at 22 in Fig. 6, while the sole is supported upon a suitable supporting table and is fed past the nozzles by suitable feeding means, there being shown in Fig. 6 a work supporting table and upper and lower feed wheels similar to the table and feed wheels shown in Fig. 2.

Preferably the cement or other stiffening medium is so applied as only partially to fill the grooves in the sole, as indicated in Figs. 7 and 8. The stiffening medium will of course penetrate more or less into the substance of the sole in the immediate vicinity of the grooves. After 10 the cement has dried it has been found that the soles have been stiffened to a substantial extent against bending about axes extending crosswise of the grooves and lengthwise of the sole. On the other hand, while the sole material in the immediate vicinity of the walls of the grooves 15 has been stiffened by means of the cement, nevertheless, the resistance of the sole to bending about axes extending lengthwise of the grooves and crosswise of the sole has been reduced by the grooving operation to such an extent that the soles have been rendered capable of bending more 20 freely about these axes than if they had not been treated. This may be due partially to the fact that the cement in each groove is not of maximum thickness throughout the entire width of the groove so that it is substantially less effective 25 to reinforce the insole against bending about axes crosswise of the sole than it is about axes lengthwise of the sole.

Having described my invention, what I claim as new and desire to secure by Letters Patent of the United States is:

1. That improvement in methods of making soles which are relatively flexible about transverse axes and relatively inflexible about longitudinal axes which consists in grooving one side of a sole in a crosswise direction, and applying stiffening material to those portions only of the sole which constitute the walls of the grooves. 5
2. That improvement in methods of making insoles which consists in forming a plurality of parallel grooves extending across an insole, and coating with stiffening material only those portions of the insole surface which constitute the 10 walls of the grooves.
3. That improvement in methods of making shoes having flexible sole parts which consists in forming a groove in the bottom surface of the forepart of an insole, the groove extending across 15 the insole, and coating the wall of the groove throughout its length with pyroxylin cement.
4. A sole having a plurality of grooves extending across it, the walls of the grooves being reinforced throughout their length by stiffening 20 material.
5. An insole having a plurality of grooves extending across it, the grooves having their walls coated throughout their length with pyroxylin cement. 25
6. An insole having a plurality of spaced grooves extending transversely of the insole, those portions only of the insole which constitute the walls of the grooves being coated with a stiffening medium and the insole material adjacent to 30 said walls being impregnated by said medium. 35

JAMES CAVANAGH.
